Albertus Larroche

UNITED STATES PATENT OFFICE.

ALBERTUS LARROWE, OF COHOCTON, NEW YORK.

SLED-BRAKE.

Specification of Letters Patent No. 24,469, dated June 21, 1859.

To all whom it may concern:

Be it known that **A**, ALBERTUS LARROWE, of Cohocton, Steuben county, State of New York, have invented an Improvement in Self-Acting Brakes for Sleighs; and I do hereby declare that the following is a full and exact description of its construction and operation, reference being had to the accompanying drawings and to the letters of reference marked thereon, so as to enable others skilled in the art to make and use my invention.

Figure 1, of the accompanying drawings represents a perspective view of a sleigh provided with my self-acting brake. Fig. 2, is a side view of one of the brake eyes R, and brake Q, the latter being represented in three different positions in full black lines, in dotted black lines, and in red. Fig. 20 3, represents one of the brake eyes.

The tongue E, of the sleigh is provided with a groove for the reception of the brake rod D.

A pin B, projecting from the front end 25 of the brake rod passes through a corresponding hole in the ferrule A, which fits loosely over the end of the tongue E. The horses are hitched to a hook C, projecting from the ferrule. The other end of the 30 brake rod is linked to a connecting rod P, which latter serves to connect the brake rod with a bent rod L O J, which latter passes at J, through the slots or brake eyes R, in the pieces U, which are fastened to the 35 frame work of the sleigh. The brake eyes are of peculiar form and serve as fulcrum for the rod L O J.

A band L, fastened around the tongue serves to prevent the brake rod D, from 40 slipping out of the notch in the tongue.

The eyener X', is pivoted to the brake rod at F.

When the horses pull the strain on the eyener causes the brake rod (to which the eyener is pivoted) to move forward together with the ferrule. This motion of the brake rod pulls the upper part L, of the rod L O J, forward so as to raise the hooks or brakes Q, at the ends of rod L O J, above the 50 ground and keep them in this position as long as the horses pull. This position of the brake is represented in Fig. 2, in full black

lines, the fulcrum of the rod L O J, being at the lower ends of the brake eyes R, R. When the sleigh commences to descend a 55 grade sufficiently steep to require the checking action of the brake, the tendency of the sleigh to descend by its own weight, pushes the front end of the tongue forward until it abuts against the front plate of the ferrule A. The horses being hitched to the hook C, of the ferrule and holding back while descending the steep grade the ferrule and tongue will remain in the same position relative to each other until the sleigh has 60 arrived at the bottom of the steep grade when the horses commence again to pull and thereby draw the ferrule forward as already described.

It will be seen that while the tongue moves 70 forward in the ferrule at the commencement of the descent of the sleigh as above set forth, the relative action of the parts is the same as if the ferrule were pushed back until its front plate abuts against the front end 75 of the tongue; the brake rod D, moving back together with the ferrule pushed back the upper part L, of the rod L O J, the lower ends of the brake eyes R, R, serving as fulcrum, and the brake hooks Q, are depressed 80 so as to engage with the surface of the road and check the tendency of the sleigh to descend by its own weight. This position of the brake is represented in Fig. 2, by dotted black lines.

Whenever the horses are caused to back the sleigh the action of the ferrule, brake rod, and upper part of rod L O J, is the same as in the case of descending a grade as above set forth, but as soon as the brake hooks touch the surface of the road, the strain on them causes the parts J, of the rod L O J, to slip back and upward in the brake eyes R, R, until resting against the upper end of said brake eyes as represented 95 by red lines in Fig. 2, when the brake hooks will just slide over the surface of the road without engaging with it and acting in the capacity of a brake.

The shape of the hollow space of the 100 brake eye R, is distinctly shown in Fig. 3; it consists of a horizontal slot 1, 2, which curves upward into a vertical slot 2, 3, as seen in said Fig. 3.

Having described my selfacting brake for sleighs what I claim therein as new and desire to secure by Letters Patent, is:—

1. Constructing the brake eyes R, R, in the peculiar form shown and described and for the purposes set forth.
2. The combination of the brake eyes R,

R, with the brake Q, substantially as described.

ALBERTUS LARROWE.
